US0D1088806S

(12) **United States Design Patent** (10) **Patent No.:** **US D1,088,806 S**
(45) **Date of Patent:** **** Aug. 19, 2025**

(54) **AIRCRAFT LATCH LOCK KEY**

(71) Applicant: **HARTWELL CORPORATION**,
Placentia, CA (US)

(72) Inventors: **Thomas J. Helsley**, Placentia, CA
(US); **Lane Dennis Dalan**, Hermosa
Beach, CA (US)

(73) Assignee: **Hartwell Corporation**, Placentia, CA
(US)

(**) Term: **15 Years**

(21) Appl. No.: **29/863,825**

(22) Filed: **Dec. 22, 2022**

Related U.S. Application Data

(60) Continuation of application No. 29/848,441, filed on Aug. 2, 2022, now Pat. No. Des. 973,463, which is a continuation of application No. 17/326,120, filed on May 20, 2021, now Pat. No. 11,773,622, which is a continuation of application No. 16/393,646, filed on Apr. 24, 2019, now Pat. No. 11,193,305, which is a division of application No. 15/510,139, filed as application No. PCT/US2015/049216 on Sep. 9, 2015, now Pat. No. 10,392,830.

(57) **CLAIM**

The ornamental design for an aircraft latch lock key, as shown and described.

DESCRIPTION

FIG. 1 is a top, front, left side perspective view showing the design according to our new design;

FIG. 2 is a front, left side perspective view thereof;

FIG. 3 is a top, rear, left side perspective view thereof;

FIG. 4 is a bottom, rear, right side perspective view thereof;

FIG. 5 is a rear, right side perspective view thereof; and,

FIG. 6 is a top, rear, right side perspective view thereof.
A head extending from a cylindrical shaft with the head having a through hole extending through both planar sur-
